Hillis.

UNITED STATES PATENT OFFICE.

ALFRED J. THOMSON, OF CANTON, MASSACHUSETTS, ASSIGNOR OF ONE-HALF TO
GEORGE H. CAPEN, OF CANTON, MASSACHUSETTS.

FASTENING OR SECURING MEANS.

1,275,176.

Specification of Letters Patent. Patented Aug. 6, 1918.

Application filed July 23, 1917. Serial No. 182,186.

To all whom it may concern:

Be it known that I, ALFRED J. THOMSON, a citizen of the United States, and a resident of Canton, county of Norfolk and Commonwealth of Massachusetts, have invented an Improvement in Fastening or Securing Means, of which the following description, in connection with the accompanying drawings, is a specification, like characters on the drawings representing like parts.

My invention relates to fastening or securing means for cords, ropes and the like. While this invention is adapted for use in a great variety of cases, it is particularly designed for use in connection with a skin-drying frame for the purpose of securing to the frame the toggle cords which are used to stretch and dry skins or hides during their treatment to produce certain kinds of leather, as patent or enamel leather.

Referring to the drawings of one embodiment of my invention illustrated and described in this application:

Figure 1 is a plan of said invention applied to a conventional form of skin stretching frame;

Fig. 2 is a detail, on an enlarged scale, of the fastening members, showing one method of using the same;

Fig. 3 is a modified form of fastening member also embodying my invention, and

Fig. 4 is a detail, of a portion of the fastening member on the line 4-4, Fig. 2, looking from the right, the staple being omitted.

Referring to Figs. 1 and 2, a frame or base 1, of suitable size and material as wood, is shown provided with a series of fastening devices or toggle fasteners, made preferably from a piece of wire or iron, according to the size required, fashioned to form a plurality of toggle gripping, open end, loops 3.

The loops herein are shown as positioned at approximately a 45° angle relative to the longitudinal strips, comprising the frame 1, to provide a more conveniently operable fastener, as will be pointed out more particularly later on.

Each loop preferably consists of an anchored bar 4, and an unanchored or free bar 5, the anchored bar being secured conveniently, as by a staple 6, to the frame

member. The two bars forming each loop are, for convenience, preferably inclined slightly toward each other, so that each loop is somewhat V shaped in form. For convenience in assembling, the bar 4 is offset downwardly somewhat at 7, Fig. 4. This enables the workman to see at a glance where the staple should be inserted, and also being naturally driven more or less into the wooden frame when the staple is inserted, the offset position answers as an additional anchorage for the loop member.

In use, the skin 8 having been placed within the frame 1, a series of toggle fasteners 9 of any approved style, are positioned upon the edge of the skin at suitable points. The cords 10 from the toggles are carried preferably as directly as possible to the nearest fastener 3, although in some instances, to stretch and hold the skin properly, it is desirable to carry the cords angularly to a fastener.

It is common at this time, to use a frame provided with fasteners in the form of closed loops, each bar of each loop being securely anchored to the frame. This fastener is positioned so that the loops extend laterally at right angles to the frame member. This type of fastener is objectionable and unsatisfactory because, both bars of the loop being anchored to the frame, they do not retain sufficient resiliency, after short use, to engage the toggle cord securely. The cord being drawn tightly beneath the loop end, is in a short time, owing to the wearing of the cord or the lessened resiliency of the loop end, brought up against the staple itself which anchors both bars of the loop, and obviously cannot be brought beyond that point, whether the loop possesses sufficient resiliency to hold the cord securely at that point or not. The result is that after the cords become somewhat smooth from wear and the loop loses somewhat its resiliency, frequently the cords slip from beneath the loops and become slack and the stretching of the skin is not effected properly.

To avoid this difficulty I have conceived the idea of anchoring one bar 4 of the loop, as stated, while permitting the other bar 5

to remain free, thus retaining in full its natural resiliency for effectively biting the toggle cord 10.

Referring to Fig. 1, it will be noticed that 5 the cord 10, is, in the usual case, carried substantially at right angles from the skin to the loop. The loop being slightly raised at its outer or closed end, and angularly positioned, as stated, the cord may be readily 10 carried beneath the loop with less difficulty than is the case where the loop is positioned at substantially right angles to the strip, as there is less danger of the cord slipping up over the loop where the cord engages it 15 angularly, rather than in a parallel direction.

In use the cord is first passed beneath the outer end of the anchored bar 4 where this bar, with the strip 1, forms a bight which 20 may be indicated *a*, and the loop presses the cord against the strip 1; the cord is then carried beneath the adjacent, outer end of the free bar 5 which also, by virtue of its own resiliency, and because it is positioned 25 upon and firmly against the strip 1, engages it and again forms a second bight, and presses upon the cord to the full extent of the resiliency of the bar, unhampered and unrestrained by any action of any anchoring 30 member. These two biting engagements by the fastener of the cord 10 will often give the necessary secure fastening of the cord. However, if desired the cord may be next carried over the bar 5, thus holding the bar 35 firmly down upon the cord beneath it at bight *b*, and the cord may be next carried again beneath the inner end of the free bar 5 where another bight *c* is formed. Here pressure by the bar 5, unrestrained and un- 40 limited by any anchoring member, is again imposed on the cord and finally it may be carried beneath the inner end of the next anchoring bar 4 to form bight *d* where it receives the full holding effect of that bar. 45 The result of the foregoing action is that the cord, by being passed under the first loop 3 receives the biting effect of two bars, one of which is anchored, and if carried beneath the inner end of the free bar and beneath 50 the end of the adjacent anchored bar, it has imposed upon it the additional biting effect of the inner end of anchored bar 4 and inner end of the adjacent unanchored bar 5, the bar 4 being held firmly down in position by 55 the cord 10, itself carried over the same substantially midway between its inner and outer ends. The bites of the free bar 5 upon the cord 10 are particularly effective, as stated, because the bar is free to exert its 60 entire resiliency upon the cord unhampered by the presence of any anchoring member.

In cases where the toggle cords do not extend at substantially right angles to the frame member 1, the full biting effect is ob-

tained however. Even though the anchored 65 bar 4 loses its resiliency to some extent through continued use, as is the case with fasteners in common use to-day, the free bar will not be so affected and will preserve its resiliency for effective action indefinitely. 70

In Fig. 3 a detail of a modified form of fastener is shown where the inner ends of the fasteners are connected by straight instead of curved lines.

In some respects the retaining of the body 75 of the wire 2 in the form of a straight connecting member for the loops, instead of curving it as in Figs. 1 and 2, possesses an advantage; as sometimes it seems to be easier to draw the cord 10 beneath the wire when 80 fashioned as in Fig. 3, because the wire presents in some cases an angular instead of a curved edge to the cord.

In either case the body of the wire connecting the loops is preferably raised slightly 85 above the frame member 1 as in the case of the closed loop end shown in Figs. 1 and 2.

While I have illustrated and described herein a preferred form of my invention, it is obvious that the same may be modified in 90 many details within the spirit of the invention and the scope of the appended claims.

Claims—

1. A cord fastening device comprising a base, and a resilient member thereon fashioned to form a plurality of oppositely directed open end loops in substantially the same plane, forming thereby two bights between the loops and the base, each pair of loops having one common anchored bar secured to the base. 95

2. A cord fastening device comprising a base, and a resilient member thereon fashioned to form a plurality of oppositely, and diagonally directed loops having a common 105 anchored bar for each pair, and providing oppositely opening bights.

3. A cord fastening device comprising a base and a wire secured thereto and fashioned to form a series of open substantially 110 parallel loops, each pair having a common offset anchored bar, and a free bar.

4. A cord fastening device comprising a base and a wire secured thereto and fashioned to form a series of open substantially 115 parallel, angularly positioned loops, having a common anchored bar, and each a free bar, the closed loop ends being alternately curved and straight.

5. A cord fastening device comprising a 120 base and a wire secured thereto and fashioned to form a series of open end loops, each having one anchored bar and one free bar, each loop providing thereby, with the base, three bights for the cord.

6. A cord fastening device comprising a base, a resilient strip member fashioned to present a plurality of open ends, substan-

tially parallel, tapering loops, one bar of each loop being secured to the base, thus providing a common free bar for each two loops, and oppositely directed cord receiving bights.

7. A cord fastening device comprising a base and a resilient member thereon fash-

ioned to provide a succession of oppositely directed open end loops, each pair of loops having a common anchoring bar extending 10 the length of the two loops.

In testimony whereof, I have signed my name to this specification.

ALFRED J. THOMSON.
